UNITED STATES PATENT OFFICE.

JOHN FREDERICK CLARK, OF LOS ANGELES, CALIFORNIA.

FLOOR POLISHER.

Application filed July 17, 1922. Serial No. 575,494.

My invention is a floor polisher adapted primarily as an attachment for vacuum cleaners of the type having a driven shaft extending toward an opening in the body thereof, and it consists in the combinations, 5 constructions and arrangements herein described and claimed.

An object of my invention is to provide an attachment of the character described 10 which includes a frame adapted to hold a polishing agent in frictional contact with a surface traversed by a cleaner to which the attachment is applied.

A further object of my invention is to provide 15 an attachment of the character described which includes means for supporting a polishing agent holding frame for reciprocation in a horizontal plane while the polishing agent is in contact with a surface traversed by a cleaner to which the attachment is applied and means for connecting the holding frame to the driven shaft of the cleaner whereby the holding frame will be reciprocated when the shaft is rotated.

Other objects and advantages of the invention will be apparent from the following 20 description and the novel features of the invention will be particularly outlined in the appended claim.

My invention is illustrated in the accompanying drawings, forming a part of this 25 application, in which:—

Figure 1 is a view, mainly in side elevation and partly in vertical section, showing 30 an attachment embodying the invention operatively applied to a suction cleaner of a well known type of construction, only such portion of the cleaner being shown as is believed to be necessary or desirable in disclosing 35 the association of the attachment therewith;

Figure 2 is a transverse vertical section through the attachment, and,

Figure 3 is a horizontal section through 40 the attachment, substantially along the line 3—3 of Fig. 2.

In Fig. 1, I show more or less diagrammatically a body 1 of a suction cleaner of ordinary construction, which body comprises 45 a motor casing 2 having an operating handle 3 pivotally attached thereto and being supported at its one end upon a steering wheel 4. The shaft 5 of a motor (not shown) which is disposed within the motor casing 50 extends into a fan casing 6 which is attached to the motor casing and ordinarily

carries a fan (not shown) which rotates with the shaft within the fan casing and causes a suction on an inlet opening 7 formed through the end of the fan casing remote 60 from the motor casing. A lip 8 is formed on the exterior of the fan casing and is adapted to cooperate with the portion of the latter encircling the opening 7 to permit of a connection of a suction nozzle or intake 65 member (not shown) of the cleaner being releasably held in attached relation to the fan casing and in open communication through the opening 7 with the interior of the fan casing 6.

The fan casing end of the body 1 is ordinarily supported upon a pair of wheels 9, only one of which is shown. The shaft 5 extends in centered relation in respect to the opening 7 and terminates within the fan 75 casing adjacent to the plane of the wall having the opening 7 therein.

The parts described so far are ordinary in construction and form no part of my invention except in so far as they cooperate 80 with the parts which will now be described.

In carrying out my invention, I provide a casing 10 comprising a pair of parallel vertical sides 11—11 having straight lower edges and substantially arcuate upper edges 85 and being joined along their upper edges by means of a cross or top member 12. The sides 11—11 and the top 12 may be formed of any suitable material, such as metal, and may be formed or cast integrally with one 90 another or separately and secured together in any suitable known manner. The casing 10 is preferably arched slightly intermediate as indicated at 13 in Fig. 2, the sides 11—11 and the top 12 being suitably formed 95 to provide the arched portion 13.

One of the sides 11 is provided with a lateral annular extension 14 concentric with an opening 15 therethrough and having at its outer end a flange 16, adapted to be received 100 between the lip 8 and the portion of the fan casing wall surrounding the opening 7 whereby the casing 10 will be releasably attached to the fan casing 6 and the opening 15 is axially aligned with the opening 7.

A crank shaft 16' has end portions journaled in horizontally aligned bearings 17—17 on the inner walls of the sides 11—11, one of the bearings 17—17 being concentric with the opening 15 and the end portion of the 110 crank shaft journaled therein being extended through the opening 15 and the annular

- extension 14 into the fan casing 6 as indicated at 18. The extended end portion 18 of the crank shaft may be enlarged adjacent to its extremity and is provided with an axial bore or socket 19 of non-circular cross sectional contour and being adapted to receive and engage a non-circular end portion of the shaft 5, whereby the latter and the crank shaft will rotate in unison.
- 10 A pitman 20 is mounted at one end upon the crank of the crank shaft and is pivotally secured at its other end between a pair of upstanding spaced ears 21-21 which are carried by attaching members 22 which are secured by screws 23 or like fastening devices to the upper horizontal member 24 of a frame which is indicated generally at 25.
- The frame 25 includes in addition to the plate-like upper horizontal member 24, which is of rectangular form, a lower horizontal member 26 which conforms substantially in area and conformation to the member 24, and vertical bar-like members 27 connecting the corner portions of the upper and lower plate-like members 24 and 26 respectively.
- The upper plate like frame member 24 is provided with lug extensions 28 extending in the plane thereof laterally of the side edges thereof and being slidably received in horizontal ways 29 defined by vertically spaced pairs of horizontal guide rods 30-30 carried at the lower edge of the sides of the casing 10, whereby the frame 25 will be supported for horizontal movement in the open lower end of the casing 10 and the lower plate-like member 26 of the frame 25 will be positioned at a level lower than that of the lower edge of the walls of the casing 10.
- 40 A polishing agent, such as a sheet 31 of a suitable fabric or other material, is extended along the under-face of the lower member 26 and is folded at its ends over the ends of the lower member 26 upon the upper face of the latter as indicated at 32-32. The portions 32-32 will be releasably clamped to the lower member 26 when clamping screws 33-33 threaded through the upper member 24 are tightened to press clamp blocks 34-34 tightly against the portions 32-32 of the polishing agent.
- 45 Openings 35-35 may be provided in the top of the casing 10 to permit access to the screws 33. The openings 35-35 are normally closed by sliding doors 36-36 adapted to be slid upwardly from closing position into pockets 37-37 in the top 12, as indicated by the dotted lines in Fig. 2.
- The casing 10 may also be provided with 60 an opening 38 in one of the sides 11 permitting access to the connection of the pitman 20 and the frame 25 and to a lubricating device (not shown) which may be positioned at such connection. A swingingly supported gravity door 39 normally closes

the opening 38. An opening 40 in the upper part of the top 12 permitting access to the connection of the pitman 20 and the crank shaft and to lubricating devices (not shown) which may be provided at such connection is 70 normally closed by a sliding door 41. The respective doors may have handles or knobs thereon for convenience in manipulating the same.

From the foregoing description of the 75 various parts of the device the operation thereof may be readily understood. The casing 10 is applied to the body 1 of a vacuum cleaner after the suction nozzle of the latter has been removed therefrom. The 80 vacuum cleaner is then moved in the usual manner on the surface that is to be polished. The crank shaft will be rotated when the motor of the cleaner is in operation, and as a result the polishing agent disposed on the 85 underside of the frame 25 will be reciprocated in frictional contact with the surface and at right angles to the direction of movement of the cleaner, whereby the surface traversed will be polished.

Obviously, the application of the attachment is not limited to that illustrated in the drawings since it is only essential to my invention that the attachment be applied to a structure having means for supporting the 95 attachment with the polishing agent in position to contact the work to be polished and having means for driving the crank shaft of the attachment at a desirable speed. For example the crank shaft of the attachment 100 may be attached to any drive shaft turning at a sufficiently low speed and the connection need not be effected within the fan casing 6, as illustrated. Moreover, the attachment may vary in details of construction from that illustrated in the accompanying drawings and I therefore consider as my own all such modifications and adaptations thereof as fairly fall within the spirit and scope of the invention as outlined in the appended 110 claim.

I claim:—

A floor polishing attachment for a vacuum cleaner comprising a casing attachable to the body of the cleaner, said casing being open at its lower end, a horizontally reciprocable frame supported in the lower end of casing, a polishing element covering the lower face of the frame for engagement with the surface on which the cleaner is supported, a crank shaft extending transversely of the casing in the upper part of the latter and extending at one end into said body of said vacuum cleaner for connection with a source of power within the latter, and a pitman connecting said crank shaft and said frame, said pitman being inclined in respect to the perpendicular at all times.
